CRIBBING

Charles Gilman, Plainfield, N. J.

Application June 7, 1941, Serial No. 397,006

7 Claims.

(Cl. 61—47)

This invention relates to cribbing and more particularly relates to improvements in precast structures of concrete and other materials which are especially adapted to holding and supporting embankments and the like.

It is an object of my invention to provide a cribbing construction in which the face of the construction will be relatively tight to prevent the earth therebehind from flowing through the cribbing and injuring the embankment, but at the same time to provide a structure which will effectively permit the drainage of water from the imprisoned earth.

It is an object of this invention to provide cribbing members having relatively broad or extended upper and lower bearing surfaces so that the stretchers may rest directly on stretchers and headers on headers without danger of crushing.

It is a further object of my invention to provide a cribbing construction in which an effective guard against lateral movement of the individual courses of the cribbing with relation to each other is provided without the necessity of rigidly attaching the courses to each other.

It is a further object of my invention to provide a cribbing structure in which a few standard parts may be simply assembled to form the complete structure, and in which certain of the parts may be utilized for more than one specific function.

It is a further object of this invention to provide a cribbing construction in which the headers which join the stretchers may be utilized in securing the ends of the construction so that the overall strength of the cribbing will be equal and the terminal section thereof will have strength equivalent to that of central portions which are supported on both sides.

It is a further object of the invention to provide intermediate stretcher anchors for anchoring the stretchers to the fill at points between the headers, thereby permitting the use of long stretchers without danger of breakage and relieving some of the stress from the headers.

Further objects and advantages will appear from the detailed description and drawings in which various preferred forms of my invention are illustrated and in which

Figure 1 is a top plan view of a cribbing assembly illustrating certain of my improvements.

Figure 2 is a view showing two courses of the assembly, partly in front elevation and partly in vertical section.

Figure 3 is an end view of the cribbing shown

in Fig. 1, with one of the T heads broken away.

Figure 4 is a section taken on the line 4—4 of Fig. 1.

Figure 5 is a section taken on the line 5—5 of Fig. 1.

Figure 6 is a detailed top plan view of a modified type of joint between the end of a header and ends of two stretchers.

Figure 7 is a vertical sectional view through a series of stretchers showing a series of intermediate stretcher anchors in elevation, the position of section being indicated by line 7—7 of Fig. 1.

Figure 8 is a rear elevation of a stretcher.

Figure 9 is a horizontal sectional view of the stretcher taken on line 9—9 of Fig. 8.

Figure 10 is a vertical sectional view similar to Fig. 7 showing a modified construction of stretcher and cooperating stretcher anchor.

Figure 11 is a sectional view taken at the position shown in line 11—11 of Fig. 10, showing portions of two stretchers and a stretcher-anchor.

Figure 12 is an end elevation of a cribbing assembly showing a corner construction which may be employed to produce a finished end wall, and

Figure 13 is a plan view of the construction shown in Fig. 12.

Referring to the drawings in detail, in Figure 30 1 is shown a composite construction of cribbing showing various arrangements of means for forming auxiliary supports between courses subsidiary to the actual connection between headers and stretchers of the same course at the extremities of the stretchers. Both stretchers and headers as well as other structural members of the wall are preferably of preformed materials such as reinforced concrete or the like.

The stretcher 11 is preferably provided with an undercut portion 13 to permit drainage. The stretcher is also provided with a zone or zones of reduced horizontal cross section 14 which permit the use of less material in the construction without depriving the stretcher of the necessary

rigidity and strength. The portions 14 are preferably joined by an integral supporting zone 15, which, as shown, in Figure 1, may be of about twice the thickness of the portions 14 and give the stretcher the necessary strength over its central zone where the vertical section, due to the cut out portion 13, is smallest.

The ends of the stretchers 11 are provided with angular flaring portions 17, zones 18 of thickness equivalent to the zone 15, and inset key portions

55 20.

The header 25 which is of the same vertical height as the end portions of the stretchers has T shaped heads 27 at each end thereof. The header is further provided with one or more notches 28 in its upper and lower edges intermediate its ends for a purpose to be described.

It will be seen that the key portions 20 of the stretchers and the T heads of the headers fit together to form a compact unit having a flat or flush front face as shown in Figure 1.

It will be seen that the enlarged end portions of the stretchers constituting the supporting zones 15 rest directly one upon another, and that the headers rest substantially throughout their length one upon another with the T heads of each header resting upon the T heads of the header below. A substantial column effect is thus produced, where the header and stretchers fit together, one course over the next, and a very strong construction is thus produced in which crushing or breakage is prevented, and particularly in which there is no danger of the heads of the headers being broken off, as sometimes occurs where the ends of the headers project between the courses of stretchers. In such constructions the headers separate successive courses of stretchers and the stretchers separate successive courses of headers, so that the compression stresses are localized at the points of intersection of the headers and stretchers, instead of being transmitted directly throughout extended bearing areas, as in the present construction.

As the headers and stretchers form horizontal courses key members are fitted in pairs of registering notches 28 to provide a positive engagement between the headers of each course so as to prevent relative slipping or displacement of one course upon the next. One form of key is shown at 30 in Figure 1 and comprises a short rectangular block of concrete received half in the notch in the upper edge of the lower header and half in the notch in the lower edge of the upper header. If desired, a plurality of these keys may be employed between each pair of headers. Short keys of the type shown at 30 in Figure 1 are preferably used if the nature of the fill is such as to require the use of back stretchers 31. For reasons of standardization the back stretchers are preferably of the form of the front stretcher 11 which has previously been described.

The key pieces 33 shown in Figure 1 have the same relation to the headers 25 as the key pieces 30 previously described. However, the keys 33 extend for a substantial distance into the ground on either side of the headers and since they provide ample anchorage for the headers very often in such a construction back stretchers may be dispensed with as shown. This is desirable where the cribbing is placed close to an existing embankment, where substantial excavation would be required for the placing of back stretchers. The headers may be placed by digging narrow trenches for them and they may be firmly anchored by the use of the long keys 33.

The key pieces may also be extended, as shown at 35 in Figure 1, to join two adjacent headers and in this construction the stability of one header will lend strength to its neighbor where such joining keys are used, no back stretchers are necessary.

In any event these key pieces 30, 33 or 35 are adapted to fit into the upper and lower notches 28 of the headers and to provide positive resistance against the shifting of one course in rela-

tion to its upper or lower neighbor. This construction obviates any necessity for positive connection between the courses in the form of rivets, dowels or the like and this insures that the cribbing construction may be completely salvaged when desired.

In constructing the end section of the cribbing it is frequently desirable to make special provision for reinforcing that section. However, it is advantageous to accomplish this result without the necessity of an additional type of concrete construction member, and I have accordingly employed for this purpose longitudinal tie members 40 which are the same as headers 25 which I prefer to extend into the fill behind and parallel to the stretchers of the end section with their ends just inside of the T heads 27 engaging the notches 28 of the shafts of end headers of the cribbing construction. The T heads engage the transverse headers and the shaft portions of the members 40 extend into the fill, thus giving ample support to the end construction of the cribbing. If header members of sufficient length are used for tie members 40, the latter will engage with the row of transverse headers next to the end headers so tying the two rows of headers together and adding additional stability. The members 40 fitting in the notches 28 also act as keys to hold the successive courses in place, and in order to make all parts interchangeable the key pieces 30, 33 and 35 are all preferably made of the same cross section as that of the header members 25 and 40 so that a standard size of notch 28 may be produced to recover any of these members.

In Figure 6 is shown a modified construction of joint between header and stretchers. This modification comprises the application of a filling material 39 between the front faces 37 of the key portions 20 of the stretchers and the rear faces 38 of the T head. This filler may be of any suitable material, preferably of a firm but somewhat yielding character such for instance as fibrous wallboard material or the like. Such material forms a cushion tending to prevent breakage of the adjacent concrete parts and also causes the cribbing to present a front wall not entirely smooth but having a pillastered appearance produced by the vertical series of slightly protruding T heads of the headers.

It is sometimes desirable to provide auxiliary anchoring means for anchoring the stretchers to the earth between successive headers. Such anchoring means are desirable in case of high walls, and the use of the same also permits the employment of comparatively long stretchers without danger of breakage. As illustrated in Fig. 2 the stretchers are preferably placed directly one above the other, and are not staggered as has sometimes been done. Accordingly if the stretchers are long, the distance between the rows of headers is comparatively great. The staggered arrangement, on the other hand, is objectionable because each stretcher has a three point bearing, and this detracts from the flexibility of the cribbing. If there is uneven settling of the fill some of the stretchers are likely to become broken in the middle. I avoid this difficulty by dispensing with the staggering of the stretchers and anchoring the stretchers between their ends by anchoring means which are flexible in the sense that the anchors are loosely connected with the stretchers, and are merely embedded in the fill so that uneven settling cannot produce stresses likely to cause breakage between the ends of the

stretchers. At the same time the stretchers are tied to the earth between their ends so that the span is not too great and the stretchers will not be broken by outward pressure of the earth.

In Figs. 1 and 7 I have shown a form of intermediate stretcher anchor 49 which is adapted to accomplish the intended purpose. The anchor comprises a shaft 50 having a short T-head 51 at one end thereof and a second head 52 at the other end thereof. The head 51 is adapted to interlock loosely with two superimposed stretchers. For this purpose the stretchers are preferably constructed as shown in Figs. 7, 8 and 9, and have a vertical opening 54 extending through the central zone 15. The rear of the central zone is cut out at top and bottom as indicated at 55 to receive the shaft of the anchor. When the stretchers are laid up with the anchor between them, as shown in Fig. 7, the headers 51 lock in the openings 54, and the shafts extend rearwardly into the earth. The rear heads 52 are of such size as to hold firmly where buried in the earth, and are preferably formed as vertically disposed T-heads, the vertical dimensions of which are equal to the height of the stretchers. Thus when the anchors are arranged one above the other as shown in Fig. 7 the head 52 of one anchor will rest loosely upon the head of the anchor below it, thus holding the anchors in proper position while the fill is being placed. At the same time there is no rigid connections so that uneven settling puts no strain upon the stretchers. The heads 51 and shafts 50 are made so as to fit quite loosely in the openings 54 and cut-outs 55 respectively, to insure this result.

In Figures 10 and 11 a modified construction of stretcher and cooperating stretcher anchor is shown. In this construction the central zones of the stretchers are provided with notches 60 in top and bottom, and in the bottoms of these notches are formed truncated conical recesses 61. The stretcher anchors 62 are provided with truncated conical projections 63 adapted to fit loosely in the recesses 61. The notches 60 are somewhat wider than the shafts of the anchors so that limited swinging movement of the anchors can take place.

The various members of the cribbing may be reenforced in any suitable manner. A suitable reenforcing arrangement for the stretchers is shown in Figs. 8 and 9. Horizontal rods 75 pass through the front part of the stretchers. To the middle one of these rods is secured a long center rod 76 which passes through the zone 15 in rear of the hole 54, while secured to the upper and lower rods 75 are a pair of shorter reenforcing rods 78 which have their adjacent ends off-set at 79 to form portions projecting into the zone 15 but terminating short of the notches 55. The outer ends of rod 76 and rods 78 preferably are off-set to extend into the key portions 20 at the ends of the stretchers. The reenforcing elements may be secured together by vertical rods such as 80.

Figures 12 and 13 show a construction which may be employed where it is desired to turn a corner or to produce a cribbing assembly having a finished end wall. As shown in these figures, the normal face of the cribbing is composed of stretchers 11 as already described. For forming the end wall, end stretchers 90 a, b, c and d which are identical with each other except in over-all length as can be seen from Figure 12. These members have end flanges 91 adapted to engage with the key portions 20 of the stretchers 11.

When the stretchers 11 are laid with a batter, as illustrated, the flanges 91 will be sloped to correspond with them, in which case the members 90 a, b, c and d will lie in horizontal courses.

5 The members 90 a, b, c and d may be held in place with respect to the stretchers 11 by stretcher anchors 49 preferably placed near the flanged ends of members 90 a, b, c and d, and the other ends of the members 90 a, b, c and d may be provided with key portions 20, adapted to be engaged by headers 25 placed at right angles to the members 90 a, b, c and d. The end wall of the cribbing may be continued to any desired length by the use of additional stretchers 11, also engaged with the headers 25.

While I have illustrated and described in detail certain preferred forms of my invention, it is to be understood that changes may be made therein and the invention embodied in other 20 structures. I do not therefore desire to limit myself to the specific construction illustrated, but intend to cover my invention broadly in whatever form its principles may be utilized.

I claim:

25 1. A cribbing construction including superimposed courses, each course having front stretchers and headers having T shaped ends interlocking with the ends of said stretchers, said headers having shafts extending rearwardly from said 30 T-shaped ends, the vertical dimensions of said headers and stretchers being such that the upper portion of a lower course is engaged by the lower portion of an upper course for a substantial part of its extent and means to prevent lateral movement of one of said courses in relation to the other said means including notches in the lower surfaces of the shafts of the headers of said upper course, registering notches in the upper surfaces of the shafts of the headers of said lower course, and key blocks interfitting in complementary 40 pairs of said notches.

2. A construction as claimed in claim 1 wherein the key blocks extend laterally from each side of the headers for a substantial distance to form 45 anchors.

3. A cribbing construction including a series of courses placed one upon the other, said courses having stretchers providing a front wall and end headers providing an end wall, said end 50 headers having complementary upper and lower notches, and tie members having longitudinally extending shafts fitting in the spaces provided by complementary pairs of said notches, said tie members having heads overlapping and engaging 55 the outer surfaces of said end headers so as to tie the end headers to the fill.

4. In a cribbing construction having a series of superimposed courses, each of said courses including front stretchers and headers engaging the ends of said stretchers and having rearwardly extending shafts, said stretchers and headers being superimposed one upon the other in column formation, the improvement which includes means intermediate the headers for anchoring 60 the stretchers to the earth, said anchoring means comprising stretcher anchors having heads interlocking with intermediate portions of the stretchers and having anchoring shafts extending rearwardly into the earth, said shafts carrying heads at their rear ends adapted to rest one upon the other when the cribbing is assembled.

5. In cribbing construction having stretchers and headers engaging the ends of said stretchers, stretcher anchors located between said headers, 70 75 said stretchers having complementary recesses

in the upper and lower surfaces thereof, and said stretcher anchors having projections loosely interlocking in the complementary recesses of a pair of adjacent stretchers, said stretcher anchors having earth engaging heads at their rear ends.

6. A cribbing stretcher having a central thickened zone having an opening formed vertically through the same, and having notches in the upper and lower faces of the zone extending from the back wall into communication with said vertical opening, said stretcher having longitudinal reenforcing rods therein at least one of which

extends through a portion of said thickened zone in rear of the vertical opening therethrough.

7. In cribbing construction, a corner assembly including front stretchers having rearwardly offset key portions at the ends thereof, and end stretchers having flange portions overlying said key portions, said end stretchers having rearwardly offset key portions at the other ends thereof, headers engaging said last named key portions and stretcher anchors connected to said end stretchers between the ends thereof.

CHARLES GILMAN.
